SPEED CONTROL FOR ENGINES

Filed Nov. 19, 1938

UNITED STATES PATENT OFFICE

2,281,883

SPEED CONTROL FOR ENGINES

Arthur Kosian, Chicago, Ill.

Application November 19, 1938, Serial No. 241,451

1 Claim. (Cl. 123—90)

This invention relates to a new and improved device for regulating the speed of internal combustion engines, particular Diesel engines.

An important object of this invention is to provide a simple yet efficient means for advancing the opening of the exhaust valves of such engines and at the same time reduce the supply of fuel and thereby reduce the speed of the engine without affecting the efficiency to any marked degree.

Another important object of this invention is to provide a means in combination with the oil supply, for advancing the opening of the exhaust valve in Diesel and other engines and accordingly control the speed thereof.

Another and further important object of this invention is to provide means whereby it is possible to slow down Diesel type of engines to any desired speed.

A still further important object of this invention is to provide effective means for efficiently operating Diesel engines at various speeds.

Other and further important objects of the invention will be apparent from the disclosures in the accompanying drawing and following specification.

The invention, in a preferred form, is shown in the drawing and hereinafter more fully described.

In the drawing:

Figure 1 is a sectional view of the device of this invention taken on the line 1—1 of Figure 2.

Figure 2 is an end view of the device of this invention with parts removed and in particular section as shown by the line 2—2 of Figure 1.

Figure 3 is similar to Figure 2 but showing the device rotated to a position it might attain when in operation.

Figure 4 is the device as shown in Figure 2 with the top part removed.

Figure 5 is a side view of the part shown in Figure 4.

Figure 6 is a view of the device of this invention and its relative positioning with reference to other related parts of the engine.

Figure 7 shows the regular cam shaft and the auxiliary cam shaft used with this invention, operating in conjunction with an exhaust valve of an internal combustion engine.

Figure 8 is a section of a part of the device as shown in Figure 1, but with the operating shaft in a different position.

As shown in the drawing:

The reference numeral 10 indicates generally a cam shaft upon which cams 12 are positioned. The device of this invention is connected to this

cam shaft as best shown in Figures 1 and 6. The device includes a gear wheel 14 which is driven from the regular source that generally drives such cam shafts. The relative angular positions between the gear 14 and the cam shaft 10 are changeable, and thus, it is possible to advance the opening of the exhaust valves when desired.

The device is enclosed in the crank case 16, broken away so as to show the important working parts. On the opposite end of the device from which the cam shaft is attached is movably positioned an operating plunger shaft 18 that enters centrally of the device to a desired distance. This shaft 18 is controlled by a foot or hand pedal 20 as best shown in Figure 6, at 20 and is connected to the shaft 18 with a link 22. The foot pedal 20 operates a throttle or control for fuel injection (not shown).

On both sides of the gear 14 are covering plates 24 and 26 forming a housing. The plate 24 has a flanged element 28 protruding out and around the periphery of the central channel 30 and, therefore, has a greater bearing surface for the plunger shaft 18. The element 28 is screw-threaded on its outside and has a packing washer 32 on its end held in position by a gland nut 34.

The covering plate 26 has a relatively large cylindrical body 36 extending to its left. The element 38 is partially positioned on the element 36 and is the only part of the device which does not have the large central channel 30.

In operation, the oil of the engine is pumped through the device. A flexible connection 48 comes from the oil pump (not shown) and is clamped on the entrance channel 42 with a clamp 44. The oil passes through the channel 46 in the link 22 and then through a central channel 48 of the shaft 18.

The distance which the shaft 18 penetrates the bore 30, will determine the effective number of openings 56 to admit the incoming oil to chamber 30. The channel 48 has its exit at 50 in an annular recessed part 52 of the shaft 18. If this shaft stops, or is stopped so that the opening 50 and the recess 52 is opposite the short exit channel 54, the oil will not enter the main portion of the device, and into the central chamber 30, and hence, the engine will operate at its normal speed, there being no change of the position of the driving gear 14 or the cams 12. In this case, the oil will exit at 54 and flow down into the sump of a crankcase 16.

As the plunger shaft 18 is pushed further in beyond the opening 54, the oil travels through the channels 56 and 58 and enters the chambers

60 and 62 respectively. Openings 72-74 are formed to open into the cut-out portions 60-62 of the element 64 which is held in firm position on the plate 24 as likewise are the other parts of the device 36 by bolts 66. Vanes 68 and 70 are permanently positioned in the rotor or geared element 14, and when these are pushed around by the incoming oil, the gear 14 is given a relative rotation with respect to element 64. The vanes will be moved only far enough to give the oil an exit. There is always sufficient space behind the rear faces of the vanes and beyond the exits of the channels 56 and 58 for entrance of oil. In other words, oil from these channels can always find its way into spaces behind the vanes 68 and 70 so as to effect relative rotation of the members 14 and 64. This exit depends again on how far the shaft 18 is pushed into its chamber 30 and the number of openings 86 exposed to release oil into chamber 30. As best shown in Figure 4, with the gear and associated parts removed, the cover plate 26 has two series of holes 72 and 74. These holes are connected by channels 76 of different depths in the element 36 as best shown in Figure 5. Each of the openings 86 on the outside of 36 are filled with plugs except the lower two, namely 78 and 80, which are left open to allow the oil to exit directly to the outside when the plunger shaft 18 has entered its full length. The channels 76 are connected with channels 82 and 84 shown in Figure 4 that have their exits 86 in the central chamber 30 as shown in Figure 1. The openings 86 can all or part be closed by the further entrance of the shaft 18. Figure 8 shows the shaft closing all but two of the openings 86. As each one of these openings 86 is closed to the passage of the oil, the gear and vanes move up to another channel to allow the oil to pass through. Each time the rotor or gear 14 changes its relative angular position with the cam shaft 10, the time the exhaust valve opens is changed. The oil passes out the openings 86 through the channel 88, and exits at 90 and thence back to the crank case. If, however, the shaft 18 is pushed in all the way, the oil exits directly to the outside through the unplugged openings 78 and 80. Figure 3 shows the gear in its relative position with adjacent parts when the shaft 18 is in as far as shown in Figure 8.

Figure 7 shows the regular engine cam shaft 92, and also the relative position of the auxiliary cam shaft 10 of the invention. These cams are shown operating an exhaust valve 94. Shown in conjunction with the exhaust valve rod is a tappet for operation with two cam shafts, namely 10 and 92. The cam shaft 92 is the regular operating cam shaft and has full control of the opening and closing of the exhaust valve, except when the cam shaft 10 is advanced to cause a sooner opening of the exhaust valve 94. The closing of the exhaust valve 94 is never effected by the advance of the cam shaft 10. The element 96 is a box-shaped part of the tappet where the regular cam shaft 92 operates.

Diesel engines operate most efficiently at a constant speed. To reduce the speed of this type

engine assuming the load remains constant, the fuel that is injected into the cylinders is reduced, but no allowance for the slower revolution is usually made. The device of this invention, when fuel is reduced, simultaneously advances the opening of the exhaust valves, and it has been shown that it is now possible to advance the opening of the exhaust valves to any desired degree with an according reduction of the fuel and vice versa and thus have the engine operate just as efficiently at slower and variable speeds. The fuel injected into the cylinders is reduced proportionately to the amount the exhaust valve openings are advanced, this occurring automatically as shown by the throttle connection in Figure 6.

Another adjustment comprises a nut 97 which is mounted on the screw-threaded rear portion of the shaft 18 so that it can be moved forwardly or rearwardly along this shaft, thereby controlling the extent or distance to which the rod 18 may enter the bore 30. Obviously, if this rod were allowed to move too far into the bore, a too great opening of the exhaust valves would result, thereby resulting in the undesired stoppage of the motor. Adjustment of this nut 97 allows of a setting whereby throttling down to a desired point may be easily effected, and the adjusting nut 97 is then locked in position by means of a lock nut 98.

This invention, therefore, is a very important step in the further development of the Diesel type engine and will make it more adaptable to many other types of work than heretofore thought possible.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

In an internal combustion engine having valves and a cam shaft, means for adjusting the timing of the exhaust valves, said means comprising an additional cam shaft operating on the exhaust valves only, driving means for said cam shaft including a gear mounted thereon and shiftable in a rotatable manner with respect thereto, means for manually controlling the rotatable driving relation of the gear to the cam shaft, said means comprising a housing formed by the gear and parts mounted on the shaft, a central cylindrical bore in the housing, a series of channels in the housing associated with the bore, hydraulic means for shifting the position of the gear in accordance with the adjustment of the manual control means, said hydraulic means including a hollow plunger shiftable within the bore to selectively control the channel openings and thereby the hydraulic means to regulate the driving relation of the gear on the shaft, and means for forcing oil as the hydraulic fluid through the plunger into the hydraulic means and through the selected opening of the series.

ARTHUR KOSIAN.
